(57) **CLAIM**

(21) Appl. No.: **29/376,992**

The ornamental design for a charging connector for electric vehicle, as shown and described.

(22) Filed: **Oct. 15, 2010**

DESCRIPTION

(30) **Foreign Application Priority Data**

Apr. 16, 2010 (JP) 2010-009667

FIG. 1 is a front, top and right side perspective view of a charging connector for electric vehicle showing our new design.

(51) **LOC (9) Cl.** **13-03**

FIG. 2 is a front, top and left side perspective view thereof.

(52) **U.S. Cl.** **D13/144**

FIG. 3 is a front elevation view thereof.

(58) **Field of Classification Search** D13/107-109,
D13/118-119, 133, 146, 147, 154, 184, 199;
D23/226; 320/104, 107-115, FOR. 104,
320/FOR. 119, DIG. 35

FIG. 4 is a rear elevation view thereof.

See application file for complete search history.

FIG. 5 is a right side elevation view thereof.

(56) **References Cited**

FIG. 6 is a left side elevation view thereof.

FIG. 7 is a top plan view thereof.

FIG. 8 is a bottom plan view thereof; and,

FIG. 9 is a front elevation view, in an alternate position

thereof.

The broken lines showing environment or structure of the

charging connector for electric vehicle are for illustrative

purposes only and form no part of the claimed design.

FIG. 10 is a front elevation view, in an alternate position

thereof.

FIG. 11 is a front elevation view, in an alternate position

thereof.

FIG. 12 is a front elevation view, in an alternate position

thereof.

FIG. 13 is a front elevation view, in an alternate position

thereof.

FIG. 14 is a front elevation view, in an alternate position

thereof.

FIG. 15 is a front elevation view, in an alternate position

thereof.

FIG. 16 is a front elevation view, in an alternate position

thereof.

FIG. 17 is a front elevation view, in an alternate position

thereof.

FIG. 18 is a front elevation view, in an alternate position

thereof.

FIG. 19 is a front elevation view, in an alternate position

thereof.

FIG. 20 is a front elevation view, in an alternate position

thereof.

FIG. 21 is a front elevation view, in an alternate position

thereof.

FIG. 22 is a front elevation view, in an alternate position

thereof.

FIG. 23 is a front elevation view, in an alternate position

thereof.

FIG. 24 is a front elevation view, in an alternate position

thereof.

FIG. 25 is a front elevation view, in an alternate position

thereof.

FIG. 26 is a front elevation view, in an alternate position

thereof.

FIG. 27 is a front elevation view, in an alternate position

thereof.

FIG. 28 is a front elevation view, in an alternate position

thereof.

FIG. 29 is a front elevation view, in an alternate position

thereof.

thereof.

FIG. 33 is a front elevation view, in an alternate position

thereof.

FIG. 34 is a front elevation view, in an alternate position

thereof.

FIG. 35 is a front elevation view, in an alternate position

thereof.

FIG. 36 is a front elevation view, in an alternate position

thereof.

FIG. 37 is a front elevation view, in an alternate position

thereof.

FIG. 38 is a front elevation view, in an alternate position

thereof.

FIG. 39 is a front elevation view, in an alternate position

thereof.

FIG. 40 is a front elevation view, in an alternate position

thereof.

FIG. 41 is a front elevation view, in an alternate position

thereof.

FIG. 42 is a front elevation view, in an alternate position

thereof.

FIG. 43 is a front elevation view, in an alternate position

thereof.

FIG. 44 is a front elevation view, in an alternate position

thereof.

FIG. 45 is a front elevation view, in an alternate position

thereof.

FIG. 46 is a front elevation view, in an alternate position

thereof.

FIG. 47 is a front elevation view, in an alternate position

thereof.

FIG. 48 is a front elevation view, in an alternate position

thereof.

FIG. 49 is a front elevation view, in an alternate position

thereof.

FIG. 50 is a front elevation view, in an alternate position

thereof.

FIG. 51 is a front elevation view, in an alternate position

thereof.

FIG. 52 is a front elevation view, in an alternate position

thereof.

FIG. 53 is a front elevation view, in an alternate position

thereof.

FIG. 54 is a front elevation view, in an alternate position

thereof.

FIG. 55 is a front elevation view, in an alternate position

thereof.

FIG. 56 is a front elevation view, in an alternate position

thereof.

FIG. 57 is a front elevation view, in an alternate position

thereof.

FIG. 58 is a front elevation view, in an alternate position

thereof.

FIG. 59 is a front elevation view, in an alternate position

thereof.

FIG. 60 is a front elevation view, in an alternate position

thereof.

FIG. 61 is a front elevation view, in an alternate position

thereof.

FIG. 62 is a front elevation view, in an alternate position

thereof.

FIG. 63 is a front elevation view, in an alternate position

thereof.

FIG. 64 is a front elevation view, in an alternate position

thereof.

FIG. 65 is a front elevation view, in an alternate position

thereof.

FIG. 66 is a front elevation view, in an alternate position

thereof.

FIG. 67 is a front elevation view, in an alternate position

thereof.

FIG. 68 is a front elevation view, in an alternate position

thereof.

FIG. 69 is a front elevation view, in an alternate position

thereof.

FIG. 70 is a front elevation view, in an alternate position

thereof.

FIG. 71 is a front elevation view, in an alternate position

thereof.

FIG. 72 is a front elevation view, in an alternate position

thereof.

FIG. 73 is a front elevation view, in an alternate position

thereof.

FIG. 74 is a front elevation view, in an alternate position

thereof.

FIG. 75 is a front elevation view, in an alternate position

thereof.

FIG. 76 is a front elevation view, in an alternate position

thereof.

FIG. 77 is a front elevation view, in an alternate position

thereof.

FIG. 78 is a front elevation view, in an alternate position

thereof.

FIG. 79 is a front elevation view, in an alternate position

thereof.

FIG. 80 is a front elevation view, in an alternate position

thereof.

FIG. 81 is a front elevation view, in an alternate position

thereof.

FIG. 82 is a front elevation view, in an alternate position

thereof.

FIG. 83 is a front elevation view, in an alternate position

thereof.

FIG. 84 is a front elevation view, in an alternate position

thereof.

FIG. 85 is a front elevation view, in an alternate position

thereof.

FIG. 86 is a front elevation view, in an alternate position

thereof.

FIG. 87 is a front elevation view, in an alternate position

thereof.

FIG. 88 is a front elevation view, in an alternate position

thereof.

FIG. 89 is a front elevation view, in an alternate position

thereof.

FIG. 90 is a front elevation view, in an alternate position

thereof.

FIG. 91 is a front elevation view, in an alternate position

thereof.

FIG. 92 is a front elevation view, in an alternate position

thereof.

FIG. 93 is a front elevation view, in an alternate position

thereof.

FIG. 94 is a front elevation view, in an alternate position

thereof.

FIG. 95 is a front elevation view, in an alternate position

thereof.

FIG. 96 is a front elevation view, in an alternate position

thereof.

FIG. 97 is a front elevation view, in an alternate position

thereof.

FIG. 98 is a front elevation view, in an alternate position

thereof.

FIG. 99 is a front elevation view, in an alternate position

thereof.

FIG. 100 is a front elevation view, in an alternate position

thereof.

FIG. 101 is a front elevation view, in an alternate position

thereof.

FIG. 102 is a front elevation view, in an alternate position

thereof.

FIG. 103 is a front elevation view, in an alternate position

thereof.

FIG. 104 is a front elevation view, in an alternate position

thereof.

FIG. 105 is a front elevation view, in an alternate position

thereof.

FIG. 106 is a front elevation view, in an alternate position

thereof.

FIG. 107 is a front elevation view, in an alternate position

thereof.

FIG. 108 is a front elevation view, in an alternate position

thereof.

FIG. 109 is a front elevation view, in an alternate position

thereof.

FIG. 110 is a front elevation view, in an alternate position

thereof.

FIG. 111 is a front elevation view, in an alternate position

thereof.

FIG. 112 is a front elevation view, in an alternate position

thereof.

FIG. 113 is a front elevation view, in an alternate position

thereof.

FIG. 114 is a front elevation view, in an alternate position

thereof.

FIG. 115 is a front elevation view, in an alternate position

thereof.

FIG. 116 is a front elevation view, in an alternate position

thereof.

FIG. 117 is a front elevation view
